(57) **CLAIM**

The ornamental design for a computer display system or portion thereof showing an animated graphical user interface as shown and described.

DESCRIPTION

The file of this patent contains at least one figure executed in color. Copies of this patent in color will be provided by the Office upon request and payment of the necessary fee.

FIG. 1 shows a first orientation of a computer display system or portion thereof showing a first image of an animated graphical user interface showing the claimed design;

FIG. 2 is a second image thereof;

FIG. 3 is a third image thereof;

FIG. 4 is a fourth image thereof;

FIG. 5 shows a first orientation of another embodiment of a computer display system or portion thereof showing a first image of an animated graphical user interface showing the claimed design;

FIG. 6 is a second image thereof;

FIG. 7 is a third image thereof, and,

FIG. 8 is a fourth image thereof.

The outermost broken lines in the figures show a computer display system or portion thereof, and form no part of the claimed design.

The appearance of the animated image sequentially transitions between the images shown in FIGS. 1-4 and FIGS. 5-8,

(Continued)

respectively. The process or period in which one image transitions to another forms no part of the claimed design.
